(57) **CLAIM**

The ornamental design for a double fluid dispenser bracket with locking mechanism, as shown and described.

DESCRIPTION

FIG. 1 is a top, front, and right side perspective view of a double fluid dispenser bracket with locking mechanism showing our new design;

FIG. 2 is a bottom front, and right side perspective view thereof;

FIG. 3 is a front elevational view thereof;

FIG. 4 is a right side elevational view thereof;

FIG. 5 is a left side elevational view thereof;

FIG. 6 is a rear elevational view thereof;

FIG. 7 is a top plan view thereof; and,

FIG. 8 is a bottom plan view thereof.

The broken-line disclosure of fluid dispensers in the views is understood to be for illustrative purposes only and forms no part of the claimed design, while the remaining broken-line disclosure is understood to represent portions of the article in which the claimed design is embodied, but which form no part of the claimed design.
